UNITED STATES PATENT OFFICE.

WILLIAM W. GALLIMORE, OF TRENTON, NEW JERSEY, ASSIGNOR TO THE AMERICAN LAMP AND BRASS COMPANY, OF SAME PLACE.

DESIGN FOR A SUPPORTING-BASE.

SPECIFICATION forming part of Design No. 30,777, dated May 16, 1899.

Application filed April 18, 1899. Serial No. 713,514. Term of patent 7 years.

To all whom it may concern:

Be it known that I, WILLIAM W. GALLIMORE, a citizen of the United States, and a resident of Trenton, Mercer county, State of New Jersey, have invented and produced a new and original Design for Supporting-Bases, of which the following is a specification, reference being had to the accompanying drawing, forming part thereof, which represents a perspective view of a supporting-base embodying my new design.

My invention relates to a design for a base for lamps or other objects; and it consists in the shape or configuration of the same, as hereinafter described and as shown in the accompanying illustration.

The leading or material feature of my de-

sign consists of a base having the form of a dragon, the legs 1 of which are partially outstretched, the neck 2 and tail 3 curved backward and toward each other to meet with the top or back of the body 4, and the head 5 resting in an upturned position, with open mouth about central on the body 4.

Having thus described my invention, what I claim as new, and desire to secure by Letters Patent, is—

The design for a supporting-base, substantially as herein shown and described.

W. W. GALLIMORE.
